MACHINE FOR REMOVING SURPLUS MATERIAL FROM BOOTS AND SHOES

Filed Nov. 30, 1925

UNITED STATES PATENT OFFICE

BERNHARDT JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY

MACHINE FOR REMOVING SURPLUS MATERIAL FROM BOOTS AND SHOES

Application filed November 30, 1925. Serial No. 72,295.

This invention relates to machines for removing surplus material from boots and shoes. The invention is illustrated as embodied in a machine designed to remove from the toe portions of unfinished boots or shoes the surplus material which results from the pulling-over and lasting operations. It is to be understood, however, that machines constructed in accordance with the present invention may be employed for removing surplus material from other portions of boots and shoes.

The toe portion of a shoe upper usually comprises the leather of the upper, the lining and a toe stiffener or toe box. In modern commercial practice the toe box, which is inserted between the upper and lining before the toe lasting operation, commonly consists of a layer or layers of felt or woven fabric impregnated with a mineral wax such as asphaltum or a compound containing such wax. Such a toe box is stiff and hard at ordinary temperatures but when moderately heated is plastic and readily conformable by the lasting machine to the shape of the toe. In this operation, however, the upper and toe box are crimped and bunched and some of the toe box wax is apt to ooze out and cling to the bunched stock.

Machines adapted to deal with the removal of this surplus crimped and bunched material around the toes of boots and shoes are disclosed in United States Letters Patent No. 1,054,656, granted February 25, 1913, on application of R. F. McFeely, and in Patent No. 1,633,855, granted June 28, 1927, on application Serial No. 694,265, filed February 21, 1924, by R. P. Frye.

Objects of this invention are to provide, without sacrificing any of the advantages of prior machines, an improved organization for performing this work which will be more effective in operation and convenient for the operator and which will more effectively dis-

pose of the waste material removed from the boots and shoes.

A feature of the invention consists in an organization comprising a perforated cylindrical abrading shell closed at one end and air-exhausting means arranged to draw air from the interior and through the perforations of the shell substantially to the exclusion of air drawn directly from about the periphery of the shell without passing through the perforations. In the illustrated machine the shell is surrounded by a casing having an opening adjacent to the open end of the shell, and a hollow member, connected with air-exhausting means, is secured to the open end of the casing, the opening in said hollow member corresponding in size to the opening in the shell so that the air-exhausting means will draw air from the interior of the shell rather than directly from the space between the shell and the casing.

Other features of the invention consists in an organization comprising a cylindrical abrading shell, a hollow sleeve carrying a disk to support one margin of the shell, a shaft extending through the sleeve, and means carried by the shaft for supporting the opposite margin of the abrading shell. In the illustrated machine the means on the shaft for supporting the shell comprises a wheel-like member the hub of which is loosely mounted on the shaft, the rim of which supports the margin of the shell, and the spokes of which support the rim and are formed as fan blades to assist in drawing air through the shell. A scraper having a plurality of blades is mounted on the shaft with its periphery close to the inner face of the shell to remove waste material therefrom and the blades of the scraper are preferably arranged at an angle to the shaft so that they also act as air-exhausting means. The arrangement is such that the sleeve and the shaft, that is, the abrading shell and the scraper blades, may be relatively rotated, for

example, in opposite directions, to enhance the action of the blades, not only in removing waste material from the inner face of the shell, but also in exhausting air through the 5 perforations of the shell.

These and other features of the invention will appear more fully from the following detailed description when read in connection with the accompanying drawings and will be 10 pointed out in the appended claims.

In the drawing,

Fig. 1 is a side elevation, partly broken away, of a machine embodying the present invention, and

15 Fig. 2 is a front elevation, partly in section, of the upper part of the machine.

In the drawing, the numeral 10 indicates the column upon which are secured bearing posts 12, 14 in which are bushings 16 which 20 form bearings for a sleeve 18. Fitted in the sleeve 18 is a shaft 20. The shaft 20 is hollow and has openings through it to the sleeve 18, oil cups being provided at the ends of the shaft 20 to supply the outer surface of the 25 shaft and inner surface of the sleeve with oil. On one end the sleeve 18 has a flange 22 to which is secured by screws 24 a disk 26. The disk 26 is provided with a flange 28 and has secured to it by screws 30 a detachable rim 32, 30 there being provided between the rim 32 and the flange 28 a space to receive the margin of an abrading shell 34. This shell may be of the type disclosed in the patent or in the application above referred to or of that disclosed in United States Letters Patent No. 1,256,574, granted February 19, 1918, on application of Knowlton and Scott, or of any 35 other type usually used for this purpose.

These abrading shells are made of sheet 40 steel and are provided with abrading projections on the outer surface and have perforations adjacent to the projections. To support the outer margin of the shell a spoke-supported rim 36 or ring is provided having in 45 its inner face a groove to receive the outer margin of the shell 34. The spokes 38, which connect the rim 36 to a hub 40, are preferably formed as fan blades to assist in exhausting air from the interior of the shell. The hub 40 has fitted into it a bushing 42 which rotates 50 freely on the shaft 20 and is held on the shaft by a collar 44 secured thereto by a set-screw 46. Thus the system comprising the sleeve 18, the disk 26, the shell 34, the rim 36, the 55 spokes 38, and the hub 40, rotate together, the system being driven by a pulley 48 secured to the sleeve 18 and driven by a belt 50 from a pulley 52 on a counter shaft 54. On the shaft 60 20 inside the shell 34 is a member 56 having a plurality of scraper blades 58, the member being split and clamped upon the shaft 20 by means of screws 60. The blades 58 are arranged at an angle to the axis of the shaft and their outer edges run in close proximity to the inner face of the shell 34. The angular ar-

angement of the blades 58 enables them to assist in exhausting air from the interior of the shell and their ends act to scrape waste material from the interior of the shell and deliver it to the air currents for removal. The shaft 20 may be held stationary but preferably, in 70 order to enhance both its scraping and its air-exhausting functions, it is rotated in a direction opposite to that in which the shell 34 is rotated. As shown, the shaft 20 has on its outer end a pulley 62 which is connected by a crossed belt 64 to the pulley 52.

In order to provide a powerful current of air through the shell and effect adequate disposal of the waste material removed by the shell, a casing 70 is provided surrounding the shell 34 and having an opening 71 in its front side for the presentation of a shoe to the outer surface of the shell. The shell 70 has an open end which is flush with the outer surface of the rim 36. Below the shell casing 70 is a fan casing 72 in which is an exhaust fan 74 driven by a belt 76 running over a pulley 78 on the shaft 54. The casing 72 has an opening in alignment with the open end of the casing 70. A U-shaped, tubular member 80 is pivoted at 82 to the fan casing 72 so that when it is swung into vertical position one opening of the member 80 will align with the opening in the casing 72 and the other opening will align with the open end of the casing 70. Preferably the size of this latter opening corresponds substantially to the inner diameter of the rim 36. The end of the member 80 is arranged to be clamped against the end of the casing 70 by means of a screw 84 pivoted at 86 to the casing 70 and disposed between lugs 88 formed on the member 80, the screw being provided with a thumb nut 90 by means of which the member 80 is firmly clamped against the end of the casing 70, a gasket being provided between the member and the casing if desired. When so clamped, the end of the member 80 will be held close to but not quite touching the rim 36. Consequently, air drawn through the member 80 by the fan 74 will be compelled to come largely from the exterior of the shell 34 through the perforations in it and will pass through the ring 36, its movement being assisted both by 110 the action of the scraper blades 58 and by the fan-shaped spokes 38. When it becomes necessary to change the shell 34, the thumb nut 90 is loosened and swung upwardly, releasing the lugs 88. The U-shaped member 80 is 115 then swung down about its pivot 82, exposing the open end of the casing 70. The set-screw 46 is then loosened and the collar 44 removed. This permits the hub 40 with the spokes 38 to be withdrawn and allows the shell 34 to be 120 pulled axially from the space between the rim 32 and the flange 28.

The air exhausted by the fan 74 passes through a pipe 92 to the exhaust system of the factory, in which a certain degree of vac-

uum is maintained. A branch 94 from the pipe 92 is connected to an opening in the casing 70. By this arrangement there is a current of air from the outside of the shell 34 through the pipe 94 to carry away any of the removed material which remains outside of the shell, while at the same time a greatly concentrated draft of air is produced through the openings in the shell 34 and through the member 80, to carry away the waste material which passes through the shell. Any of this material which tends to collect on the interior of the shell is scraped or torn loose by the blades 50 and disposed of by the powerful currents of air, as described.

Having thus described my invention, what I claim as new and desire to secure by Letters Patent of the United States is:

1. In a machine of the class described, the combination of a perforated abrading shell closed at one end only, means for rotating the shell, and air-exhausting means arranged to draw air from the interior of the shell and through the perforations substantially to the exclusion of air drawn from about the exterior of the shell without passing through the perforations.

2. In a machine of the class described, the combination of a perforated, cylindrical, abrading shell open at one end, a casing substantially surrounding said shell, and air-exhausting means connected to said casing adjacent to the open end of the shell in such manner that air will be drawn from the interior of the shell and through its perforations substantially to the exclusion of air drawn directly from the space between the shell and casing.

3. In a machine of the class described, the combination of a perforated, hollow, abrading shell having an open end, a supporting ring for the open end of the shell, a casing substantially surrounding said shell having an opening in a plane adjacent to the plane of the ring, and air-exhausting means provided with a duct secured to the casing and having its opening in close proximity to the ring.

4. In a machine of the class described, the combination of a perforated, hollow, abrading shell having an open end, a supporting ring for the open end of the shell, a casing substantially surrounding said shell having an opening in a plane parallel to the plane of the ring, and air-exhausting means provided with a duct secured to the casing and having an opening corresponding in size to the opening in the ring, the end of the duct being in close proximity to the ring.

5. In a machine of the class described, the combination of a perforated, cylindrical, abrading shell open at one end, a ring supporting the shell at its open end, a casing partially surrounding said shell, and air-exhausting means connected to the casing

adjacent to the opening in the ring and having an opening of substantially the inner diameter of the ring so that air will be drawn through the ring from the interior of the shell.

6. In a machine of the class described, the combination of a perforated, cylindrical, abrading shell open at one end, a casing partially surrounding said shell, air-exhausting means connected to said casing adjacent to the open end of the shell in such manner that air will be drawn mainly from the interior of the shell and through its perforations, and separate connections for drawing air directly from the space between the shell and casing.

7. In a machine of the class described, the combination of a cylindrical abrading shell, a hollow sleeve having a disk for supporting one margin of the shell, a rotary shaft extending through said sleeve, means on the shaft mounted for rotation relatively thereto for supporting the opposite margin of the shell, and means carried by the shaft for exhausting the air within the shell.

8. In a machine of the class described, the combination of a perforated, hollow, abrading shell having an open end, a supporting ring for the open end of the shell, a casing substantially surrounding said shell having an opening adjacent to the ring, and air-exhausting means provided with a duct secured to the casing, the end of the duct being in close proximity to the ring.

9. In a machine of the class described, the combination of a cylindrical abrading shell, a sleeve, a shaft extending through the sleeve, means for rotating the sleeve and shaft, a disk secured to the sleeve, a wheel-like member having its hub supported on the shaft for rotation relatively thereto and corresponding in diameter to the disk, the disk and the rim of the wheel-like member having means to hold the abrading shell thereon, and means carried by the shaft for exhausting the air within the shell.

10. In a machine of the class described, the combination of a sleeve, a shaft extending through the sleeve, means for rotating the sleeve and shaft, a disk secured to the sleeve, and a wheel-like member having its hub rotatably supported on the shaft and having the same diameter as the disk, the opposed faces of the disk and the rim of the wheel-like member having grooves to receive a cylindrical abrading shell.

11. In a machine of the class described, the combination of a sleeve having a disk, a shaft extending through the sleeve, means for rotating both the sleeve and shaft, a wheel-like member having its hub supported on the shaft for rotation relatively thereto, a cylindrical abrading shell mounted upon the disk and the rim of the wheel-like member, and a scraper carried by the shaft located in close proximity to the interior of the shell.

12. In a machine of the class described, the combination of a hollow abrading shell having an open end, a shaft extending through said shell, a scraper on said shaft having blades arranged with their ends in close proximity to the interior of the shell, and a member for supporting the shell at its open end. 5
13. In a machine of the class described, the combination of a hollow abrading shell having an open end, a shaft extending through said shell, a scraper on said shaft having blades arranged with their ends in close proximity to the interior of the shell and formed as fan blades for exhausting air through the open end of the shell, and a member for supporting the shell at its open end comprising a rim and a plurality of spokes formed as fan blades to augment the action of the scraper 10 blades. 14. In a machine of the class described, the combination of a perforated abrading shell closed at one end only, means for rotating the shell, air-exhausting means arranged to draw air from the interior of the shell and through the perforations substantially to the exclusion of air drawn from about the periphery of the shell, and a scraper for cleaning the interior surface of the shell. 15
15. In a machine of the class described, the combination of a sleeve having a disk, a shaft extending through the sleeve, means for relatively rotating the sleeve and shaft, a wheel-like member having its hub supported on the shaft, a cylindrical abrading shell mounted upon the disk and the rim of the wheel-like member, and a scraper secured on the shaft and clearing the inside of the shell. 20
16. In a machine of the class described, the combination of a cylindrical abrading shell, a hollow sleeve mounted for rotation and having a disk for supporting one margin of the shell, a shaft extending through said sleeve and mounted for rotation independently thereof, means comprising a spoke supported rim having a hub mounted on the shaft for supporting the opposite margin of the shell, and means carried by the shaft for removing waste material from the inner face of the shell. 25
17. In a machine of the class described, the combination of a perforated, cylindrical, abrading shell open at one end, a ring supporting the shell at its open end, a casing substantially surrounding said shell, air-exhausting means connected to the casing adjacent to the opening in the ring and having an opening of substantially the inner diameter of the ring so that air will be drawn through the ring from the interior of the shell, and supplemental connections to the casing through which air may be drawn directly from about the exterior of the shell. 30
18. In a machine of the class described, the combination of a perforated, hollow, abrad- 35
- ing shell having an open end, a supporting ring for the open end of the shell, a casing partially surrounding said shell having an opening adjacent to the ring, air-exhausting means provided with a duct secured to the casing, the end of the duct being in close proximity to the ring, and other connections to the casing through which air may be drawn from the space between the shell and the casing. 40
